UNITED STATES PATENT OFFICE.

CHARLES F. BEST, OF QUEENS, NEW YORK.

WAGON-BRAKE.

SPECIFICATION forming part of Letters Patent No. 309,125, dated December 9, 1884.

Application filed August 28, 1884. (No model.)

To all whom it may concern:

Be it known that I, CHARLES F. BEST, a subject of the Queen of Great Britain, residing at Queens, in the county of Queens and 5 State of New York, have invented new and useful Improvements in Wagon-Brakes, of which the following is a specification.

My invention relates to improvements in devices for operating the brake-heads of 10 wagons and other vehicles; and it consists in the combination, with a brake-head and its connection with the brake-rod, of a hand or foot lever, a socket formed on said lever, a 15 brake-rod lever, and a knuckle formed on said lever and fitting the socket in the hand or foot lever.

This invention is illustrated in the accompanying drawings, in which Figure 1 is a side elevation of my improved brake mechanism. 20 Fig. 2 is a front elevation of the same. Fig. 3 is a perspective view of a wagon provided with the same.

Similar letters indicate corresponding parts. The letter A indicates the frame to which 25 part of the brake mechanism is attached, said frame being secured to the dash-board of the wagon. B is the hand or foot lever, pivoted to the frame A, by the bolt or pin a. c is a socket formed in the lower end of the hand or 30 foot lever B. C is the brake-rod lever, pivoted to the frame A by a bolt or pin, d, and formed with a knuckle, e, on its upper end, which enters the socket c in lever B. The lower end of the brake-rod lever C is connected with the 35 brake-rod D by the pin or bolt f.

As shown in the drawings, the brake-rod D is extended to and connected with two levers, g g', suspended from the wagon-body by bars h h', and connected directly with the brake- 40 heads i i', both levers g g' being moved at the same time by motion, as of the brake-rod D. Instead of this arrangement, the brake-rod D may connect with an intermediate lever which is connected with a single brake-head by 45 means used in the ordinary construction and arrangement of such connections.

In the accompanying drawings the full lines represent the relative positions of the levers B C and the brake-rod D when the 50 brake-heads i i' are applied to the wheels, and the broken lines show the same when the brake-heads i i' are drawn off the wheels.

In the operation of the brakes, when the hand or foot lever B is moved forward, the front wall of the socket c engages the knuckle 55 f on the brake-rod lever C, causing the said lever C to be moved to an extent required for throwing the brake-head i i' upon the wheel.

When the hand or foot lever B is moved backward, the back wall of the socket c engages the knuckle E, and the brake-rod lever 60 D is moved to an extent required to remove the brake-heads i i' from the wheels.

If desired, the effect of the relative backward and forward motions of the hand or foot 65 lever B may be reversed—that is to say, by moving the lever B backward the brake-heads i i' may be applied, and by moving the same forward they may be removed from the wheels—such an arrangement being more convenient 70 when the lever B is operated by hand.

The object of this invention is to secure 75 brake mechanism which is exceedingly simple in its construction and at the same time safe and durable.

Heretofore a brake mechanism has been composed of a plate to which is pivoted a foot-lever having at its lower end a pin engaging a longitudinal slot in the upper end of a brake-rod lever, also pivoted to said plate and connected at its lower end to the brake-rod. My 80 invention differs from such prior construction, in that I form a solid knuckle on the upper end of the brake-rod lever, which knuckle is received into a socket formed within the lower 85 end of the foot or hand lever, whereby a stronger connection of the parts is provided.

What I claim as new, and desire to secure by Letters Patent, is—

The combination of the brake-rod D and 90 the pivoted brake-rod lever C, having the solid knuckle e formed on its upper extremity, with the pivoted lever B, having the socket c within its lower end, which receives the knuckle on the upper end of the brake-rod 95 lever, substantially as described.

In testimony whereof I have hereunto set my hand and seal in the presence of two subscribing witnesses.

CHARLES F. BEST. [L. S.]
